UNITED STATES PATENT OFFICE.

ALFRED H. KIDNEY, OF ORANGE, NEW JERSEY.

SCREEN FOR THE SEPARATION OF ORES.

1,131,710.

Specification of Letters Patent.

Patented Mar. 16, 1915.

Application filed December 11, 1913. Serial No. 805,972.

To all whom it may concern:

Be it known that I, ALFRED H. KIDNEY, citizen of the United States, residing at Orange, in the county of Essex and State of New Jersey, have invented certain new and useful Improvements in Screens for the Separation of Ores, of which the following is a specification.

My invention relates to an improvement 10 in screens for the separation of ores, and the object is to provide screens so constructed and arranged that they can be reversed in the shaking frame at the will of the operator.

15 During the screening operation the screens become clogged, and the customary process has been to remove the screens and apply wire brushes to the reverse side of the screen for removing the material from the screen. This treatment of the screens is very 20 detrimental. The clogging alone proportionately lessens the screening capacity, and seriously affects the sizing function. To overcome this defect, I have provided a 25 screen which can be reversed, so that the material which has become bound in the meshes of the screen will be removed when the screen is reversed, and by the vibration of the screen during the operation of the 30 machine.

Another object is in the provision of a distributor which is connected to the shaking frame for distributing the material onto the screen. By this method, the ore is distributed easily and gradually onto the screen, and thereby saves the life of the screen and overcomes the serious objection of discharging the ore directly from the 35 hopper onto the screen.

40 A further object is in the provision of flexible supporting means for the shaking frame, and the agitating means for imparting a bumping action to the shaking frame, whereby the shaking frame receives reciprocal movement and counter-radial movements.

The invention consists of still other novel features of construction and combinations of parts which will be hereinafter more 50 fully described and pointed out in the claims.

In the accompanying drawings: Figure 1 is a top plan view; Fig. 2 is a longitudinal vertical sectional view. Fig. 3 is a top plan view showing two screen sections connected together; Fig. 4 is a longitudinal vertical

sectional view of the screens; Fig. 5 is a transverse vertical sectional view of the shaking frame on the line 5—5 of Fig. 3; Fig. 6 is a detail view showing the spring 60 plate connected to the head end of the shaking frame; Fig. 7 is a vertical sectional view through an end of the machine and movable frame showing the manner of mounting buffer springs; Fig. 8 is a view of one of the 65 brackets for holding the buffer spring in elevation; Fig. 9 is an enlarged detail view showing the manner of mounting an edge of the lip or plate in the side of the screen frame; and Fig. 10 is a transverse vertical 70 sectional view of the shaking frame on the line 10—10 of Fig. 3.

A represents the supporting frame, and B is the shaking frame. The upper end of the frame has a steel plate 1 connected thereto. 75 The lower end of the plate is provided with slots 2, 2, through which screw threaded hand wheels 3, 3 extend, and which are connected to the frame A for adjustably holding the upper end of the shaking frame. 80 The lower end of the shaking frame is suspended by a similar plate 4, which is connected to a bracket 5 on the frame A. The plate 1 affords an adjustment for the shaking frame, and changes the inclination of 85 the shaking frame, the head end of the frame being at a higher elevation than the lower end. Springs 6 are located between the forward end of the shaking frame B, and the frame A for forming a buffer for 90 the frame during its movement.

The recessed disks 6^a are connected to the forward end of the frame B in which an end of the springs 6 are received, the other terminal of the spring 6 being received in the 95 recessed portion of the adjustable brackets 7^a. These brackets 7^a are provided with elongated slots 7^b. A screw passes through the frame A and through the elongated slot 7^b of the bracket 7^a for fastening the bracket 100 to the frame. When the head of the shaking frame B is moved by the adjustment of the plates 1, it is necessary to change the position of the springs 6 and this can be accomplished by means of the screw 7 and the 105 slots 7^b of the brackets 7^a.

The cam shaft 8 is journaled at the lower end of the frame A, and is provided with cams 9, 9. These cams are adapted to engage the lower end of the shaking frame B 110 and cause the frame to move toward the head end of the frame A, and then allow

the frame to come back and strike the cam, producing a bumping action. A drive pulley 10 is connected to the shaft for transmitting motion thereto. The movement of the frame is reciprocal, and this movement produces a counter-radial movement by reason of the like movements of the plates which is created by the tripping cams at the foot of the frame working against the spring 6, 10 which also provides for impacts in such a manner that free movement of the shaking frame is obtained, and impacts with minimum of friction, and most highly effective vibratory effect is communicated to the screens, inducing rapid screening action with minimum of mesh clogging.

The frame B is provided along its longitudinal inner sides with a bead or mold 11, upon which the screens are mounted. 20 Mounted upon the moldings are a plurality of screens or sieves, and each screen is provided with a frame 12, made in two sections, and interposed between the sections is the screen fabric 13, which is of any desired 25 mesh. The screens are preferably made up of different meshes, as for instance, some are made of sixty, eighty, and a hundred mesh, but I do not wish to be limited to the exact size of mesh, as some ores will require a 30 finer mesh, and others a coarser mesh, and it is my intention to use the mesh of screen which will give the most satisfactory results.

At each end of the screen frame openings 14, 14 are formed on each side of the screen, 35 and connected to the screen fabric 13 at each end are plates 15, 15. The plates are held in place by tension rods 16, and the sections of the frame are connected together by means of screws 17, 17 for fastening the 40 fabric and plates therebetween. The tension rods 16 are provided for affording the proper tension of the screens at their ends, and during some operations it is necessary to use more rods than during others. For instance, I have found three tension rods sufficient in fine screens above sixty, and two rods in screens of sixty mesh and coarser.

At the head of the shaking frame B a transverse recess 18 is formed in which an 50 end of one of the lips or plates 15 is received. As all of the screens are made alike, provision must be made for the head screen and the recess 18 is therefore provided for the reception of the lip or protruding plate 15. 55 The screens are arranged within the shaking frame B in accordance with the wishes of the operator, and the fine mesh screen can be located at the head of the shaking frame, or at a lower point.

60 The lips or plates 15 overlap, that is, the lips of two adjacent sections underlap and overlap, so that there is no interference or interruption in the screening operation, as the ore will pass from one screen onto the 65 next, and so on throughout a number of

screens mounted in the shaking frame. The lips or plates 15 are located or received in V-shaped recesses 18^a, at their ends, so that the outer edge of the lips is capable of moving vertically. This flexibility of the lips 70 affords an easy connection between the lips of the adjacent sections, as without this flexible connection the jointure of the two adjacent lips would be too rigid.

Connected to the shaking frame B are 75 hoppers 19 for the reception of material passing through the screens. Should any of the screens become clogged, the operator can remove the clogged screen and reverse it, or change its position within the frame B. 80 This reversing feature is very important, as clogged meshes are most effectively cleared by the vibration transmitted to the screens, and the reverse feed pressure.

The joining of the several screens together so that the ore will pass from one screen to the other, produces a continuous screening field of varied meshes, and as each screen is capable of being reversed without interfering with the other screens, the 90 screens can be kept cleaned without the necessity of removing the screens from the frame and subjecting them to a brushing action to remove the material therefrom.

A distributor 20 is mounted upon the shaking frame B above the screen 13. The distributor 20 extends transversely of the frame B, and is provided with suitable openings or perforations through which the ore may pass onto the head screen. The ore or 100 material will be caused to pass through the openings by the vibrations and movements of the frame B. The ore is fed from a hopper 21 to the distributor 20. The object of the distributor is to overcome the objection of 105 discharging the material directly from the hopper onto the bed screen, which is injurious to the screen fabric. The sieving distributor not only arrests the feed before reaching the screen, but also prevents undue 110 friction of same and distributes the ore in a very gentle manner entirely across the screen, which is essential to full screening capacity.

A sliding plunger 22 is located beneath 115 the hopper 21 for feeding the ore into the distributor 20. The plunger 22 is reciprocated by means of a rod 23, which is connected to the plunger by means of a yoke 24. This rod 23 is eccentrically and adjustably 120 connected to a shaft 25 mounted upon the frame A. A pulley wheel 26 is mounted upon the shaft, and a pulley 27 on the shaft 8. A belt 28 connects the pulleys 26 and 27, 125 whereby motion is transmitted to the shaft 8 upon the rotation of the shaft 8 for causing the plunger to be actuated for discharging the ore from the hopper into the distributor.

The movement which is transmitted to the 130

5 screens by the cams 9 is indicated by the dotted lines in Fig. 2, and as the frame is forced against the spring 6, a rebound is obtained, forcing the frame back against the cams, the spring plates 4 and 1 permitting the frame to move longitudinally of the frame A. The vibrations, which will be transmitted to the screen by this action, will cause the ore, as it is discharged from the 10 distributer due to vibrations received by the distributer, to separate upon the various screens and pass into the hopper. The ores which are oversized or too large to pass through the meshes of the screens will pass 15 over the lower ends of the lowermost screen, and into a chute 29. The screen frames each being opened at both ends and on both sides of the screens permits the oversized ores, and in fact, all of the ores, to pass from 20 one screen to another until the proper mesh is obtained for the ores to pass through.

Of course as the ore passes over the screens, some of the ore will be too large to pass through the screens, and will continue 25 to pass from one screen to another until the last screen is reached, where the ore will pass from the screen over the lower edge thereof and into the chute 29.

I claim:

30 1. The combination with a shaking frame, of a screen frame reversibly mounted within the shaking frame, said shaking frame having openings formed on both sides of the screen and end thereof, so that the large 35 particles which will not pass through the screen may be discharged at the end thereof.

2. The combination with a movable frame, and means for transmitting a vibratory movement thereto, of a plurality of screens 40 invertibly mounted in said frame, and means

for conducting the material from one screen to another in either position of the screens.

3. The combination with a movable frame, of a plurality of invertible screen frames mounted in the frame, a distributer connected to the movable frame for distributing the matter to one of the screens, of means for transmitting a vibrating movement to the frame for discharging the material from the distributer onto the screens, and for causing 50 the material to pass through the various screens.

4. The combination with a frame, of a movable frame, flexible means supporting said movable frame upon the first-named frame, means for imparting vibratory movement to said movable frame, and invertible screens mounted in the movable frame.

5. A screen comprising a frame having 60 fabric connected to the walls thereof, said frame provided with openings on both sides of the screens at the ends thereof.

6. The combination with a frame, of a plurality of screen frames, invertibly and 65 interchangeably mounted therein, said screen frames having communication with each other.

7. The combination of a frame with a plurality of screen frames having screening 70 fabric mounted therein, and flexible lips connected at the ends of the screening fabric so that the lips of the adjacent sections will form an overlapping jointure.

In testimony whereof I affix my signature, 75 in the presence of two witnesses.

ALFRED H. KIDNEY.
